CONTROL MECHANISM FOR WATER
HEATING SYSTEMS

William J. Griffiths, Toronto, Ontario, Canada

Application February 3, 1933. Serial No. 655,062

7 Claims. (Cl. 137—144)

This invention relates to control mechanism intended particularly for automatically maintaining a predetermined pressure in a water heating system. A device for this purpose requires the use of two valves one opening to admit water under pressure from a source of supply when the pressure in the system falls below a predetermined minimum and the other opening to permit water to escape from the system when the pressure therein increases above a predetermined maximum. In the present invention my object is to devise a common control for both valves, thus avoiding double adjustments and enabling closer regulation to be obtained.

A further object is to devise a special arrangement in connection with the inlet valve whereby the latter will rapidly open and remain fully open until sufficient fresh water has been brought into the system to restore the pressure and which will then move rapidly from the unseated to the seated position, thus enabling a quick filling of the system to be obtained.

A still further object is to devise a construction which will itself act as a safety valve in the event of the pressure within the system rising to near a dangerous degree, and thus avoid the necessity for using a separate safety valve in the system.

I attain my object by means of the constructions hereinafter specifically described and illustrated in the accompanying drawing in which

Fig. 1 is an elevation, partly in section, of my improved control apparatus with the inlet valve open; and

Fig. 2 is a vertical section with inlet valve closed and exhaust valve open.

In the drawing like numerals of reference indicate corresponding parts in the different figures.

Referring to the drawing, 1 is a hollow valve body formed with a threaded connection 2 by means of which the device may be connected with a water heating system. In the body are formed the inlet opening 3 and the outlet opening 4.

Connected with the valve body 1 is the inlet valve casing 5 which is provided with an inlet connection 6 adapted to be connected to a supply of water under pressure. The valve casing 5 is formed with a valve seat 7 at the end of and 50 in axial alignment with the inlet opening 3. The valve 8 is adapted to engage the seat and is provided with a fluted guide extension 9 slidable through the valve seat and opening 3.

Opposite the valve seat 7 an opening is formed 55 in the valve casing 5 through which the valve

may be inserted and which is closed by a threaded cap 10.

The lower end of the valve 8 is connected with a metallic bellows 12, the lower end of the latter being provided with an annular flange 13 by 60 means of which it may be clamped between the end of the body 5 and cap 10.

A passage 14 is formed through said valve 8 and extension 9 communicating with the interior of the metallic bellows, and in this passage is slidable the stem 11 of a valve 15 which is adapted to lie against a valve seat 16 at the lower end of the valve 8. A spring 17 engaging the under side of the valve and the inner surface of the cap 10 normally tends to hold the valve 15 seated. The 70 valve 15 is provided with a post 18 to hold the spring in place. A by-pass 19 is provided through the valve 8 between the interior of the bellows 12 and the interior of the valve casing 5 for a purpose which will hereinafter appear.

The passage 19 is preferably provided with an adjusting screw 42 by means of which the amount of flow through said passage may be controlled.

The passage 14 and the stem 11 are so shaped relative to one another as to permit the flow of 80 water along said passage when the valve 15 is unseated. In the preferred form the passage is circular in cross section while the stem is square in cross section.

In order that the pressure required for the unseating of the valve 15 may be adjusted, the stem 11 is adjustably connected with said valve. This is accomplished by providing a threaded hole in the valve 15 and extension 18 in which the threaded end of the stem 11 is fitted.

A screen 41 is preferably positioned about the valve 8.

Connected to the body, is a housing 20 through one end of which is formed a passage in alignment with the outlet 4, and through the side of which is formed an outlet 21. At the end of the passage 22 is formed a valve seat 23 on which is adapted to seat a valve 24, which is provided with a fluted stem 25 slidable in the passage 22. The other end of the housing 20 is open, but is normally closed by a plug 26 threaded in said open end. A spring 27 bearing against the end of the plug normally tends to hold the valve 24 seated.

To actuate the valves I provide the following mechanism. The upper end of the valve body 1 105 is provided with a removable closure plate 28 by means of which a metallic bellows 29 may be secured in position by means of its flange 30, which is clamped between the closure plate and the valve body. The lower end of the bellows is 110

provided with a plate 31 to which is secured the member 32 through which the valves are operated, said member being provided at one side with a laterally extending arm 33 which is adapted 5 under certain conditions of the system to actuate the stem 11 to unseat the valve 12.

This member 32 is provided with a lug 34 which is adapted to engage one end of a lever 35 pivoted on a post 36 formed on the head of the 10 housing 20. The other end of this lever is adapted to engage the end of the fluted stem 25 of the valve 24.

The plate 31 of the bellows is engaged by one 15 end of a coil spring 37. The other end of the spring bears against a plate 38 carried by or controlled by a screw 39 threaded through the closure plate 28 whereby the pressure of said spring on the plate 31 may be adjusted. The pressure of the spring, however, must be such that, 20 when the pressure in the system falls below a predetermined minimum, the pressure tending to collapse the bellows 29 is insufficient to balance the coil spring 37.

The operation of the apparatus is substantially 25 as follows. Should pressure in the system exceed a predetermined maximum said pressure will cause the bellows 29 to contract at the same time raising the member 32 and causing the lug 34 to engage and rock the lever 35 to push down 30 on the stem 25 and thus unseat the valve 24, allowing escape through the outlet 4, the passage 22, the housing 20 and outlet 21, the latter being preferably connected with a drain. As the pressure drops, the bellows 29 will return to its normal 35 condition, thus relieving pressure on the stem 25 from the lever 35 and allowing the spring 27 to again seat the valve 24.

Assuming now the pressure drops below a predetermined minimum, the bellows 29 expands 40 and the arm 33 on the member 32 engages the stem 11 and unseats the valve 7, thus allowing the water within the bellows 12 to escape through the passage 14, the pressure of the water acting on the outside of the bellows 12 contracts the 45 latter and unseats the valve 8, thus allowing water to enter the system through the passage 3. As the pressure in the system increases due to the inflow of water the bellows 29 is contracted thus 50 relieving pressure of the arm 33 on the stem 11 and allowing the valve 15 to seat. Water then enters the interior of the bellows 12 through the passage 19, but at a very restricted rate due to the small size of said passage, and as the pressure 55 within and without the bellows 12 becomes equalized, the spring 17 which seated the valve will, through continued pressure on the latter, quickly move the valve 8 to seated position, thus closing the inlet 3.

It will be seen that through the comparatively 60 large area of the bellows plate 31 relative to the size of the valves, the device is very effective in providing a positive opening for the exhaust valve 24.

It will also be seen that the valve 24, being arranged 65 so that pressure within the system tends to unseat it, acts as an efficient safety valve thus avoiding the provision of a special safety valve in the system.

From the above description it will be seen that 70 I have devised a construction which will satisfactorily attain the objects of my invention as set forth in the preamble of the specification.

What I claim as my invention is:

1. In a control device for water heating systems, a hollow body member adapted for com-

munication with said system and having an inlet and an outlet opening; an inlet passage with which the inlet opening communicates; valves controlling said openings from without the body; springs tending to close said valves; a stem on said outlet valve projecting within the body; inlet valve control means extending within the body; a valve actuating member adapted to engage the inlet valve control means; a lever pivoted within the body, one end of said lever being adapted to engage the stem of the outlet valve, and the other end of the lever being adapted to be engaged by the valve actuating member; a spring tending to move the valve actuating member in one direction; and means actuatable by fluid pressure in the chamber tending to move said member in the reverse direction. 80

2. In a control device for water heating systems, a hollow body member adapted for communication with said system and having an inlet and an outlet opening; valves controlling said openings from without the body; springs tending to close said valves; a stem on said outlet valve projecting within the body; inlet valve control means extending within the body; a valve actuating member adapted to engage the inlet valve control means to unseat the inlet valve when said valve actuating member moves in one direction; means operable by the valve actuating member for unseating the outlet valve when 100 said valve actuating member moves in the other direction; a spring tending to move the valve actuating member in one direction; and means actuatable by fluid pressure in the chamber tending to move said member in the reverse direction, 105 said hollow body member having an opening for connection with a water heating system.

3. In a control device for water heating systems, a hollow body member adapted for communication with said system and having an inlet 110 and an outlet opening; an inlet passage with which said inlet opening communicates; a valve controlling the outlet opening; a valve controlling the inlet opening, said inlet valve having a passage formed axially therethrough; a bellows 120 chamber of which said passage forms the outlet; a valve within the bellows chamber controlling said outlet passage; a stem for said valve extending through said passage into the hollow body member; means normally tending to hold 125 said last mentioned valve and the inlet valve seated, said bellows chamber having a restricted inlet; and means within the hollow body member for actuating the first mentioned outlet valve and the bellows chamber outlet valve to unseat 130 said valves.

4. In a control device for water heating systems, a hollow body member adapted for communication with said system and having an inlet and an outlet opening; an inlet passage with 135 which said inlet opening communicates; a valve controlling the outlet openings; a valve controlling the inlet opening, said inlet valve having a passage formed axially therethrough; a bellows chamber of which said passage forms the outlet; 140 a valve within the bellows chamber controlling said outlet passage; an adjustable stem for said valve extending through said passage into the hollow body member; means normally tending to hold said last mentioned valve and the inlet valve 145 seated, said bellows chamber having a restricted inlet; and means within the hollow body member for actuating the first mentioned outlet valve and the bellows chamber outlet valve to unseat 150 said valves.

5. In a control device for water heating systems, a hollow body member adapted for communication with said system and having an inlet and an outlet opening; an inlet passage with which said inlet opening communicates; a valve controlling the outlet opening; a valve controlling the inlet opening, said inlet valve having a passage formed axially therethrough; a bellows chamber of which said passage forms the outlet; a valve within the bellows chamber controlling said outlet passage; a stem for said valve extending through said passage into the hollow body member; means normally tending to hold said last mentioned valve and the inlet valve seated, said bellows chamber having an adjustable restricted inlet; and means within the hollow body member for actuating the first mentioned outlet valve and the bellows chamber outlet valve to unseat said valves.
- 20 6. In a control device for water heating systems, a hollow body member adapted for communication with said system and having an inlet and an outlet opening; an inlet passage with which said inlet opening communicates; a valve controlling the outlet openings; a valve controlling the inlet opening, said inlet valve having a passage formed axially therethrough; a bellows chamber of which said passage forms the outlet; a valve within the bellows chamber controlling said outlet passage; an adjustable stem for said valve extending through said passage into the hollow body member; means normally tending to hold said last mentioned valve and the inlet valve seated, said bellows chamber having an adjustable restricted inlet; and means within the hollow body
- member for actuating the first mentioned outlet valve and the bellows chamber outlet valve to unseat said valve.
7. In a control device for water heating systems, a hollow body member adapted for communication with said system and having an inlet and an outlet opening; an inlet passage with which said inlet opening communicates; a valve controlling the outlet opening having a stem extending within the body member; a valve controlling the inlet opening, said inlet valve having a passage formed axially therethrough; a bellows chamber of which said passage forms the outlet; a valve within the bellows chamber controlling said outlet passage; a stem for said valve extending through said passage into the hollow body member; means normally tending to hold said last mentioned valve and the inlet valve seated, said bellows chamber having a restricted inlet; means within the hollow body member for actuating the first mentioned outlet valve and the bellows chamber outlet valve to unseat said valves comprising a valve actuating member adapted to engage the stem of the bellows chamber outlet valve; a lever pivoted within the body, one end of said lever being adapted to engage the stem of the first mentioned outlet valve, and the other end of the lever being adapted to be engaged by the valve actuating member; a spring tending to move the valve actuating member in one direction; and means actuatable by fluid pressure in the chamber tending to move said member in the reverse direction.
